[57] CLAIM

The ornamental design for a vessel, as shown and described.

DESCRIPTION

FIG. 1 is a perspective view of the vessel;
FIG. 2 is a right-side elevational view of the vessel;
FIG. 3 is a front elevational view of the vessel;
FIG. 4 is a rear elevational view of the vessel; and,
FIG. 5 is a perspective view of an alternative embodiment of the vessel, which is the same in appearance as that of FIGS. 1-4 with the hard top deleted.
